UNITED STATES PATENT OFFICE.

KARL R. SLOCUM, OF DRYBRANCH, GEORGIA.

EXCAVATING APPARATUS.

1,283,932.

Specification of Letters Patent.

Patented Nov. 5, 1918.

Application filed June 17, 1918. Serial No. 240,474.

To all whom it may concern:

Be it known that I, KARL R. SLOCUM, a citizen of the United States, residing at Drybranch, in the county of Twiggs and State of Georgia, have invented new and useful Improvements in Excavating Apparatus, of which the following is a specification.

This invention relates to slack line excavators of the elevated type or that class in which the shovel or scoop and carrier or supporting means therefor are unitedly movable over an elevated cable or track adapted to be lowered or raised during the operation 15 of the carrier and shovel or scoop and in accordance with the specific function and operation of the shovel or scoop. The main object of the invention is to render excavators or excavating apparatus of this class more 20 easily and positively controllable as to digging or filling, conveying and dumping operations thereof at points distant from a power source solely by manipulation of the power elements and without utilizing stop 25 means on the elevated cable or track or check devices located adjacent to the cable or track by embodying within the carrier and shovel or scoop organization devices directly actuated as to the performance of their 30 several functions, as for instance in retaining the load during travel and reversal of movement after stoppage of the shovel or scoop for dumping the load from the power source and whereby the shovel or scoop may be lowered or raised at any point along the line of 35 the cable or track and also relieved of its load by dumping at any point desired along the length of the cable or track. A further object of the invention is to use a single 40 cable as a track and readily operable from a source of power to slacken or lower the same and elevate it as may be necessary, and a carrier movable on said track and provided with a shovel or scoop connected by a 45 draft cable to the power source controlling also the track cable to quickly and regularly manipulate the carrier and shovel as a whole, particularly during digging, filling or loading and dumping operations of the shovel 50 solely from the power source and to effect the several operations specified at any point or distance along the line of the track cable as may be found desirable.

A structure or organization embodying 55 features of the invention is illustrated in the drawings and will be fully hereinafter de-

scribed to demonstrate one practical application of the invention, and in the drawings:

Figure 1 is a diagrammatic sectional elevation of the excavating apparatus embodying the features of the invention and showing a complete installation, a complete cycle of operation being shown in full and dotted lines.

Fig. 2 is an enlarged side elevation of the power source showing the controlling means thereof.

Fig. 3 is an enlarged side elevation of the carrier and shovel or scoop showing parts in different positions in dotted lines.

Fig. 4 is an elevation looking toward the side of the carrier opposite that shown by Fig. 3 and also illustrating a part of the shovel or scoop.

Fig. 5 is a top plan view of the carrier.

Fig. 6 is a transverse vertical section taken in the plane of the line 6—6, Fig. 3.

Fig. 7 is a perspective view of the carrier and shovel or scoop, a part of the track cable and the operating cables for the shovel and carrier and between the latter and the carrier, the carrier being broken away and parts removed therefrom.

Fig. 8 is a detail sectional elevation particularly illustrating the pawls and ratchets coöperating with the tripper head and showing the pawls centrifugally released from the ratchet which occurs during down grade movement of the carrier and shovel.

Fig. 9 is a sectional side elevation of the carrier showing the pawls and ratchets of the tripper head in working position or the pawls engaging the ratchet, which occurs during the filling operation of the shovel and also during the dumping operation of the latter.

Fig. 10 is a transverse vertical section taken in the plane of the line 10—10, Fig. 8.

Fig. 11 is a detail elevation of the cam hub and disk illustrating the means for adjusting the cam which effects the full release of the mechanism of the carrier after the shovel has dumped.

The numeral 5 designates a power source disposed upon a suitable base 6 and comprising essentially two drums 7 and 8 adapted to be rotated for winding purposes by the usual mechanical connections operated by an engine or motor, the drum 7 having a brake device, for instance a strap brake 9 with a controlling foot lever 10 and the drum 8 provided with a strap brake 11 with a con-

trolling foot lever 12, the foot levers 10 and 12 being operated to check the movement of the drums when desired or found necessary. Adjacent to the source of power is an A-frame 13 which may be of any approved type and embodying an upper sheave 14, a block 15 adjacent to the sheave, and a cable block 16 having a track cable 17 connected thereto. From the drum 8 a cable 18 passes upwardly over the sheave 14 and through the block 16 and then through the block 15 and again forwardly through the said block 16, and by means of this arrangement of the cable 18 the necessary tautness and slack 10 of the cable 17 may be readily controlled. The cable 17 in the present instance is elevated by a mast 19 to increase the height of the dump. The track cable 17 inclines from the top of the A-frame 13 downwardly to the 20 mast 19, the latter mast being located a suitable distance from the power source and A-frame, preferably about five hundred feet. The exact distance, however, of location of the mast 19 from the A-frame and power 25 source is not essential and may be varied. The drum 7 is engaged by a draft cable 20 which runs over a sheave 21 in the lower portion of the A-frame, said draft cable being connected to the excavating means *per se* 30 as will be hereinafter explained.

The essential feature of the invention comprises a carrier 22 and a shovel or scoop 23. As clearly shown by Figs. 3, 4, 5 and 6, the carrier 22 comprises opposite sheet metal 35 side plates 24 suitably shaped and of such width as to provide proper housings and bearings for the parts carried thereby and having mounted in the upper portions of the front and rear extremities thereof spindles 40 or shafts 25 and 26 which are rotatable in suitable bearings and respectively carry track sheaves 27 and 28 held in engagement with the track cable 17 which passes between the side plates 24 of the carrier, as clearly shown 45 by Fig. 6. The side plates 24 will be suitably braced or connected at the bottom as at 29, and at the top as at 30. Depending from the side plates 24 adjacent to the track sheaves 27 are hangers 31 which are laterally 50 expanded from the carrier, as shown in Fig. 6, and pivoted or hinged at their lower ends between lugs or ears 32 projecting from the rear side 33 of the shovel or scoop 23. The lower ends of the hangers 31 are attached to 55 the rear end of the shovel or scoop below the longitudinal center of the latter so as to effect a practical dumping operation of the shovel or to permit the same to assume such angle when released that the contents there- 60 of will freely fall therefrom. On the spindle or shaft 26 carrying the track sheave 28 a tripper head 34 is mounted adjacent to one of the side plates 24 and comprises a casing 35 which is keyed to said shaft and 65 has a plurality of pawls or dogs 36 pivotally

mounted therein and provided with weighted free ends 37, as clearly shown by Figs. 8, 9 and 10. Adjacent to the casing 35 a bushing 38 is mounted on the shaft 26, and rotatably disposed on this bushing is a disk 39 having a hub 40, said disk being loose for rotation and provided with a segmental projection 41 which forms a striker for a purpose which will be presently explained. Secured to the disk 39 and located within the 70 casing 35 for coöperation with the pawls or dogs 36 is a ratchet 42. From the foregoing it will be seen that a clutch organization is provided by the casing 35 keyed to the shaft 26 and carrying the pawls or dogs 36 and the 75 ratchet 42 secured to the disk 39 carrying the segmental striker projection 41 and whereby the said disk 39 and striker projection may be operated at intervals or when the carrier is moving in one direction. The casing 35 with the pawls or dogs 36 and the disk 39 80 with the segmental striker projection 41 and ratchet 42 will be hereinafter termed concretely a striker head having a rotation in part at intervals to perform a releasing operation which will be presently described. At an intermediate point the side plates 24 have opposite or transversely alined bearings 43 and therein a shaft 44 is mounted to 85 rotate. The shaft 44 projects outwardly beyond the bearings 43, as shown by Fig. 6, and on one end thereof is keyed a hub 45^a of a disk 45^b adjustably supporting a control ratchet 45, and on the opposite extremity of this shaft is a hub 46 with a disk or casting 47, as shown by Fig. 11, the said disk or casting 47 being provided with a series of circumferential holes 48 designed on the plan of a double vernier gage for ease in making adjustment of a cam 49 which is 90 similarly provided with openings 50 to register with the openings 48, this cam being secured to the disk in its adjusted position by means of suitable fastenings 51, as clearly shown by Fig. 4. On the shaft 44 between the side plates 24 two friction sheaves 52 and 53 are keyed so that all of the parts carried by the shaft may move together or have an equal rotation when the control ratchet 45 is released. The control ratchet 45 is normally engaged by a lock, generally indicated by 54, and consisting of a bolt or latch 55 mounted in suitable guides 56 secured to the side plate 24 adjacent to the control ratchet 45; and surrounding this bolt or latch 55 between the guides 56 is a spring 57 which tends to maintain the nose or free end 58 of the bolt or latch 55 in locking engagement with the teeth of the control ratchet 45, as shown by Fig. 3. A cable 59 continues forwardly from the bolt or latch 55 and is secured to an upright release lever 60 attached at its lower end to a rock shaft 61 mounted in suitable bearings and extending transversely across the carrier and projecting 100 105 110 115 120 125 130

outwardly beyond the side plates 24. The upright release lever 60 is held in near contact with the casing 35 of the striker head 34 and is shifted forwardly by the segmental striking projection 41 of the striker head 34 to release the control ratchet 45 by withdrawing the bolt or latch 55 from engagement with the teeth thereof. On the end of the shaft 61 opposite that carrying the 5 release lever 60, as shown by Fig. 4, is a release crank 62, and on the same side of the carrier the lower end of a cam lever 63 is fulcrumed and has its upper end movable in a slotted cam lever bracket 64. Between the 10 release crank 62 and cam lever 63 is a pitman rod 65, and when these parts are in normal position they will appear as shown by Fig. 4 in full lines, the release crank being essentially perpendicular and the cam lever 15 63 inclined toward and engaging the concentric portion 66 of the cam 49.

The shovel or scoop 23 is similar to the usual devices of this type and is provided with a closed back and an open front end as 20 well as a closed bottom, the bottom at the front end of the shovel or scoop being formed as a cutting edge and provided with a set of teeth 67. Above the bottom a suitable distance, draft plates 68 are secured to 25 opposite sides of the shovel or scoop, and over the front extremity extends a bail 69 securely fastened to the opposite sides of the shovel, as clearly shown by Figs. 3 and 7. This bail is suitably braced and stiffened and 30 has top centering projections 69^a. The draft cable 20 is connected by a suitable coupling eye or other device 70 to a draft yoke 71 comprising a diverged cable 72 adjustably secured to the draft plates 68 and engaged by 35 a spreader or yoke bar 73. Secured to a center attachment 69^b of the bail 69 is a flexible dumping control means consisting of a cable 74 which passes upwardly to, over, and downwardly around the friction sheave 52, and from the coupling 70 an actuating cable 40 75 passes to the lower portion and partially over the friction sheave 53 so that the cables 74 and 75 engage their respective friction sheaves in reverse positions and whereby 45 50 when the one unwinds from its friction sheave it will wind the other on the remaining friction sheave. To facilitate the movement and easy action of the cables 74 and 75, grooved direction sheaves 76 and 77 are 55 mounted between the lower forward portions of the side plates 24 of the carrier on a shaft 78 for respective engagement by the said cables 74 and 75. These direction sheaves or pulleys 76 and 77 also operate to 60 65 hold the cables 74 and 75 in proper operating position relatively to the friction sheaves 52 and 53.

In the operation of the excavator or excavating apparatus the shovel or scoop 23, together with the carrier 22, is lowered by

slackening the cable 17 by suitable operation of the rear drum 8 of the power mechanism until the shovel rests upon the ground, sufficient slack being given to the cable 17 to permit the shovel to remain in contact with the ground. The rear drum 8 is then checked by its brake means as explained and the front or draft drum 7 is released and operated to wind the draft cable 20 thereon, thus drawing the shovel with the carrier forwardly and causing the front end of the shovel to dig into the ground and deposit a load therein as shown at A by full lines in Fig. 1. During this forward movement of the shovel in loading, the track sheave 28 necessarily rotates on the cable 17 in a direction to cause the tripper head 34 to operate or rotate therewith and bring the segmental tripper projection 41 into engagement with the release lever 60, said release lever being 85 thrown forwardly and returned to its initial position because the segmental tripper projection 41 acts as a weighted head and falls downwardly as soon as passing the center of contact with the release lever 60, having this freedom because of ratchet arrangement specified, but no release of the shovel control ratchet will be effected in view of the fact that the shovel is resting on the ground surface or its teeth in the act of digging 90 which necessitates a strain on draft cable 20, part of which is transmitted to actuating cable 75 which through the sheave mechanism holds the shovel in a state of control, which means that lock 54 is in practically 100 constant engagement with control ratchet 45. When the shovel is filled the front drum 7 will be checked in its movement and immediately thereafter the slack of the track cable will be taken up by operating the rear drum 105 8, and by continued winding of the track cable on the latter drum the carrier 22 with loaded shovel 23 will be elevated to the height desired and there held by applying the brake mechanism of the back drum as 110 shown at B in dotted lines by Fig. 1. During the time that track cable 17 is being elevated, the front drum 7 is released so that the draft cable 20 may loosely pay off therefrom in view of the fact that the cable 17 is 115 at an inclination, and the carrier with loaded shovel will immediately start to gravitate or move. This gravitation or movement of the carrier and shovel over track cable 17 is permitted to continue until the point is reached 120 where it is desired to dump the loaded shovel, and when such point is reached the drum 7 is again checked in its movement and said latter drum is given a winding operation from the power source, as shown at C 125 by dotted lines in Fig. 1. It will be understood that when the carrier and shovel are running down the track cable, that, due to centrifugal force, the heads of the pawls or dogs 36 will fly out against casing 35, the 130

said pawls or dogs remaining in this position until the carrier and shovel come to nearly a stop and then the said pawls or dogs engage the ratchet 42 running in the direction of the ratchet teeth. The said pawls or dogs lock in engagement with the ratchet at the moment of reversing the direction of travel which is practically the point of dump. The shovel and carrier now being 10 reversed and the pawls 36 locked in ratchet 42, the tripper head 34 is caused to rotate which brings segmental projection 41 into engagement with release lever 60 which throws said release lever forward and pulls 15 lock 54 from the control ratchet 45 and the shovel starts to dump. Before the projection 41 is entirely released from lever 60 the cam 49 will have been turned in such forward position as to bring the cam projection 20 thereof in full engagement with the cam lever 63 owing to the fact that a downward pull on the friction sheave 52 will have ensued through the cable 74 by reason of the shovel falling to dump, and, as a consequence, 25 the cam lever 63 will be pushed forwardly, as shown by dotted lines in Fig. 4, and, likewise, the release crank 62, a distance sufficient to hold the release lever 60 clear of the projection 41 of the tripper head 34, thereby also holding the nose or end 58 of the bolt or latch 55 of the lock 54 clear of control ratchet 45 which is now being rotated very rapidly, due to the shovel falling to dump. The shovel will drop to a position 35 nearly perpendicular and the load therein will be discharged when the critical angle is reached. When the shovel falls to the position of dump, for instance, shown by Fig. 7, the cable 74 will have unwound from its 40 friction sheave 52 and at the same time the cable 75 would have been wound on its friction sheave 53. It will be understood that the dumping of the shovel takes place almost immediately at start of return flight, the performance taking place regardless of 45 speed or load. The only stop or intermittent flight is at that time when the shovel and carrier are reversed in their motion.

From the foregoing it will be seen that the 50 carrier and shovel are controlled in their flight relatively to the track cable when moving to a point of dumping by the brake mechanism in connection with the front drum, after the shovel is dumped the carrier and shovel are brought back to the point of loading or digging. When the shovel or 55 carrier are drawn at an upward inclination over the track cable 17, the shovel hangs downwardly at an angle depending upon the 60 per cent. of grade of track cable 17, and in this position every part of the carrier mechanism is in a state of release, with the exception of the tripper head, which rotates independently and free of contact with relation to the release lever 60 by reason of the 65

fact that the cam 49 is still holding the release lever through the connection explained so far forward as to clear the projection 41 of the tripper head. The shovel and carrier are then again lowered to the ground 70 surface, the teeth end of the shovel striking the ground first, and on continued lowering the shovel comes to its correct loading position through the hinge connection on the back of the shovel. As soon as the teeth of 75 the shovel strike the ground and the shovel commences to close, the weight of the pull-bar connection plus the idle weight of the pull-line causes cable 75 to unwind from and at the same time rotate its friction sheave 80 53 and simultaneously rotate the friction sheave 52 in the same direction to effect a winding of the cable 74 on the friction sheave 52 which releases the cam mechanism so that the control ratchet 45 will be in position 85 for instant engagement by the lock when the shovel will have again become loaded.

What is claimed is:

1. An excavating apparatus having a 90 power source embodying drums with controlling means, a track cable operatively associated with one of the drums, a carrier with a shovel movably held thereby and mounted on the track cable, and a draft 95 cable operatively associated with the remaining drum and connected to the shovel and carrier, the carrier having mechanism to hold the shovel elevated during travel independently of the draft cable and operable 100 by the draft cable to release and dump the shovel.

2. An excavating apparatus having a power source mechanism, a track cable operatively associated with the power source mechanism, a draft cable also associated with the power source, and a carrier movably engaging the track cable and provided with a shovel having a dumping association therewith, the draft cable being connected 110 to the shovel and carrier and the latter provided with mechanism to hold the shovel elevated during travel independently of the draft cable and operable through the draft cable and a part of the power source mechanism to dump the shovel at any point desired along the track cable.

3. An excavating apparatus comprising a power mechanism and track and draft cables movably associated with parts of the 120 said power mechanism, and a carrier movable on the track cable and provided with a shovel having a dumping association therewith, the draft cable being connected to the carrier and the latter having means to hold the shovel elevated during travel independently of the draft cable and operable from the power mechanism through the draft cable to dump the shovel at any point desired along the track cable.

4. An excavating apparatus comprising power mechanism, a track cable engaging a part of the power mechanism and having raising and lowering movements imparted thereto by the said mechanism, a draft cable also associated with the power mechanism, and a carrier provided with a shovel movably held thereby, the carrier being mounted to gravitate on the track cable and having a mechanism for holding the shovel elevated independently of the draft cable and operable to release and dump the shovel, the release mechanism and the shovel having the draft cable connected thereto and controlled solely for the power mechanism to dump the shovel at any point along the track cable.
5. An excavating apparatus comprising a slack track cable having rising and falling movements imparted thereto, power mechanism with which the track cable co-operates, a dumping shovel provided with means gravitantly mounted on the slack track cable, a draft cable connected to the shovel, and release mechanism to hold the shovel elevated independently of the draft cable and operable from the power mechanism through the medium of the draft cable to dump the shovel at any point along the length of the track cable.
6. An excavating apparatus comprising power mechanism, slack track and draft cables associated with said mechanism, and a shovel and carrier mounted to gravitantly move on the track cable and connected to the draft cable, the carrier and the power mechanism having co-operating mechanisms conjointly operative to release and dump the shovel by actuation from the power mechanism and at any point along the length of the track cable, the mechanism of the carrier operating to hold the shovel elevated independently of the draft cable.
7. An excavating apparatus embodying power mechanism with cable drums, a track cable having supports and operable in connection with one of said drums to slacken and lower and raise the same, a carrier and shovel mounted to gravitantly move over said track cable, and a draft cable operatively connected to the remaining drum and to the shovel and carrier, the carrier having means for holding the shovel elevated independently of the draft cable and operative by the draft cable and the drum to which the draft cable is connected for controlling the dumping operation of the shovel at any point along the length of the track cable from the power mechanism.
8. An excavating apparatus having power mechanism embodying drums with controlling means, a track cable operatively associated with one of the drums, a draft cable operatively associated with the remaining drum, and a carrier with a shovel movably held thereby and to which the draft cable is connected, the carrier being provided with automatically operative mechanism to hold the shovel elevated independently of the draft cable and including locking means which is released by the draft cable and controlled from the power mechanism to dump the shovel at any point along the length of the track cable.
9. In an excavating apparatus, a track cable, a draft cable, power mechanism with which said cables are associated, a carrier having sheaves to engage the track cable, a tripper head movably associated with the forward sheave, a control ratchet having friction sheaves operable therewith, a lock for the control ratchet, release mechanism primarily operated by the tripper head to disengage the control ratchet, secondarily operating final release means to hold the lock free of the control ratchet, and a shovel movably connected to the carrier and having cables engaging the friction disks associated with the control ratchet, the draft cable being attached to the shovel and a part of the release mechanism.
10. In an excavating apparatus, power mechanism, a slack track cable and a draft cable operatively associated with the power mechanism, a carrier provided with track sheaves engaging the track cable, one of the sheaves having an automatically operating tripper head rotatable with its sheave when the carrier is moved in a forward direction, a control ratchet, a lock for the control ratchet, release means connected to the lock and engageable by the tripper head, final release means connected to the control ratchet and operating to hold the lock in disengaged position relatively to said ratchet to permit the tripper head to run free, a shovel movably connected to the carrier, and means between the shovel and the control ratchet for permitting the shovel to be dumped automatically and to be held in load-carrying position relatively to the carrier, the draft cable being connected to the shovel and carrier.
11. An excavating apparatus comprising a rising and falling track cable, power mechanism with which the track cable co-operates, and excavating means mounted to have a gravitating movement on the track cable and including a draft cable, a shovel and devices for holding the shovel elevated independently of the draft stress on the said draft cable and connected to a part of the power mechanism for releasing the shovel and dumping the same at any point along the track cable from the power mechanism.
12. An excavating apparatus comprising a track cable, an excavating means including a shovel and movable on the track cable and also raised and lowered by the latter, power mechanism with which the track cable co-operates, and connected devices in part em-

- bodied in the power mechanism and in part comprised in the excavating means and responsively operative by the actuation of the part of the power mechanism to dump the excavating means at any point along the track cable, the mechanism of the excavating means being operative in part to hold the shovel thereof elevated independently of the power mechanism.
- 10 13. An excavating apparatus comprising a rising and falling track cable, power mechanism with which the track cable coöperates, and excavating means mounted to have a gravitating movement on the track cable and embodying a shovel and carrier, the latter having devices for retaining the shovel elevated during travel independently of the power mechanism and pulling stress on the carrier and shovel and having a reversal of movement after a stoppage of the carrier and shovel controlled from the power mechanism to dump the shovel and whereby the latter with the carrier may be lowered or raised at any point along the line of the track cable.
- 15 14. An excavating apparatus comprising a rising and falling track cable, power mechanism with which the track cable coöperates, and excavating means mounted to have a
- gravitating movement on the track cable 30 and including a carrier and shovel, the carrier being provided with mechanism for holding the shovel elevated and locked against dumping movement independently of any pulling stress exerted thereon from the power mechanism and also operable from the latter mechanism for unlocking and releasing the shovel at any point desired along the track cable.
- 20 15. An excavating apparatus comprising 40 a rising and falling track cable, power mechanism with which the track cable coöperates, and excavating means mounted to have a gravitating movement on the track cable and including a shovel and carrier, the carrier 45 also having adjustable means for locking the shovel in elevated position independently of pulling stress from the power mechanism and also operable from the latter mechanism for unlocking and releasing the shovel at 50 any point desired along the track cable.

In testimony whereof I have hereunto set my hand in presence of two subscribing witnesses.
